VARIABLE-WIDTH SCANNING VIEWER

Vincent Grippi, Jr., Novato, and William D. Johnson,
Santa Clara, Calif., assignors to Houston Fearless Corporation, a corporation of California

Filed July 30, 1965, Ser. No. 86,373

Term of patent 3½ years

(Cl. D61—1)

FIG. 1

FIG. 2

FIG. 3

FIG. 4

FIG. 6

FIGURE 1 is a side perspective view taken from the front and one side of a variable-width scanning viewer showing out new design;

We claim:

The ornamental design for a variable-width scanning viewer, substantially as shown.
